UNITED STATES PATENT OFFICE.

JAMES BARTON KAIGHN, OF PHILADELPHIA, PENNSYLVANIA.

PREPAYMENT MECHANISM.

1,159,227.

Specification of Letters Patent.

Patented Nov. 2, 1915.

Application filed June 22, 1910. Serial No. 568,283.

To all whom it may concern:

Be it known that I, JAMES BARTON KAIGHN, of Philadelphia, in the State of Pennsylvania, have invented a certain new and useful Improvement in Prepayment Mechanism, whereof the following is a specification, reference being had to the accompanying drawings.

My invention relates to coin controlled vending machines and is particularly applicable to gasometers wherein a rotary coin carrier may be operatively connected by a coin with a valve which may then be manually set in position to deliver a predetermined quantity of gas.

It is the usual practice in constructing a prepayment gasometer to locate the valve controlling the passage of gas through the meter within the casing of the latter, and to locate the prepayment mechanism exterior to said gasometer casing, and, in order to assemble the two devices in co-operative relation various preliminary adjustments are necessary.

The form of my invention hereinafter described is advantageous in that both the gas controlling valve and the prepayment mechanism are assembled in a single casing or box distinct and primarily separate from the meter casing to which it is subsequently attached, and, in that same box also includes a receptacle for the coins used in operating the prepayment mechanism.

My invention includes the combination with a valve controlling the passage of gas through the meter, of an externally screw threaded shaft arranged to alternately operate said valve in connection with the prepayment mechanism and in connection with the gasometer mechanism; said shaft being axially shifted in one direction to open said valve by operation of the prepayment mechanism, and axially shifted in the opposite direction to close said valve by operation of the meter mechanism, said shaft being prevented from rotating during the opening movement of the valve and being rotated during the closing movement of the valve as hereinafter described.

My invention also includes the various novel features of construction and arrangement hereinafter specified.

In the drawings:—Figure I is a front elevation of a box conveniently embodying my

invention, in connection with a gasometer. Fig. II is an elevation of the left hand side of said box as shown in Fig. I. Fig. III is an elevational view, similar to Fig. I but omitting the removable cover plate of the gear chamber in said box. Fig. IV is an inside view of said cover plate showing the coin inlet shutter mechanism. Fig. V is a plan sectional view, taken on the line V, V in Fig. IV. Fig. VI is a vertical sectional view, taken on the line VI, VI in Figs. I and III. Fig. VII is a vertical sectional view, taken on the line VII, VII in Figs. I and III. Fig. VIII is a vertical sectional view, taken on the line VIII, VIII in Figs. I and III. Fig. IX is a plan sectional view, taken on the line IX, IX in Figs. I, III, VI, VII and VIII. Fig. X is a plan sectional view, taken on the line X, X in Fig. VIII. Fig. XI is a front view of the axially movable screw shaft and its housing removed from the box. Fig. XII is a plan view of the gear housing shown in Figs. X and XI. Fig. XIII is a plan sectional view of said housing, taken on the line X, X in Fig. VIII. Fig. XIV is a plan view of the rotary coin carrier, clutch ring, clutch disk and the exterior handle operatively connected therewith. Fig. XV is a plan view of the rotary coin carrier. Fig. XVI is a front view of said coin carrier. Fig. XVII is a front view of said clutch ring.

In said figures: 1 is the casing of the gasometer containing meter mechanism which may be of any ordinary construction. The prepayment mechanism box 2 is distinct and primarily separate from said casing 1 but is conveniently soldered to the latter. Said box 2 is provided with the gas inlet tube 3 having the screw thread 4 for connection with a gas supply pipe and leading into the valve chamber 5 within said box. The valve seat port 6 opens from said valve chamber 5 into the gas chamber 7 within said box 2, having the port 8 opening into said meter casing 1 as shown in Fig. VI. As indicated in Fig. III said box 2 includes in addition to said valve chamber 5 and gas chamber 7 the gear chamber 9 and coin chamber 10. The passage of gas through said port 6 and consequently through the meter is controlled by the valve 12 which as shown in Fig. VI is connected by the pivot 13 with the arm 14 on the rock shaft 15 which is journaled

gastight in the stuffing box bearing 16 shown in Fig. IX. Said shaft 15 extends within the gear chamber 9 where it has the yoke 17 engaging the axially movable screw shaft 18 which being mounted for vertical reciprocation in the housing 19, shown in Fig. XI removed from the box, may be raised by the prepayment mechanism to open said valve 12 and lowered by the meter mechanism to close said valve, as hereinafter described.

As shown in Figs. VIII and IX, the valve operating lever yoke 17 overhangs said screw shaft 18, extending in the path of the latter, when said valve 12 is closed; so that when 15 said shaft is raised by the operation of the prepayment mechanism, upon the insertion of a coin, said yoke is thrust aside to immediately open said valve to the extent shown in Fig. II. Said yoke being then 20 supported in raised position by bearing upon the circumference of said shaft, further upward movement of said shaft, consequent upon the insertion of other coins, does not change the position of said yoke or 25 valve. However, when as the consequence of the dispensation of gas and operation of the meter mechanism, said shaft 18 is lowered to its initial position, said lever yoke 17 is again lowered over the upper end of said shaft 18 30 permitting said valve 12 to close by its own weight but it is positively forced upon its seat 6 by the overhanging head on said shaft 18 pressing upon the top of said yoke 17.

Said screw shaft 18 extends through the 35 nut gear 20 which is supported by the lower wall 21 of said housing 19, in engagement with the idle gear 22 also supported by said wall 21 and journaled on the stationary stud shaft 23 as shown in Fig. VII. Said gear 40 22 has its teeth beveled to engage the bevel gear 25 which is rigidly connected by the screw 26 with the shaft 27 of the coin carrier 28. Said carrier shaft 27 is journaled in the removable housing plate 30 and is 45 prevented from accidental rotation by the triangular plate spring 31 which bears upon said plate 30 and upon the collar 32 which is engaged with said shaft by the pin 34, as shown in Fig. VII. Said coin carrier 28 50 has the diametrically opposite projections 35 which as shown in Fig. III are recessed to receive a coin, conveniently a silver quarter of a dollar 36 which may be dropped therein through the coin inlet slot 38 in the wall 39 55 of said box 2, said wall being a cover for said gear chamber 9, normally rigidly connected with said box, but removable as hereinafter described. Said coin inlet slot 38 registers with the slot 41 in the circular arc 60 flange 42 of the rotary coin clutch ring 43, which may be freely oscillated upon said plate 30 except when a proper coin 36 is inserted therein as shown in Fig. III, such oscillatory movement being only limited by 65 the abutment screw 44 projecting from said

plate 30 to encounter the opposite ends of said flange 42. As shown in Fig. IV the clutch disk 45 has diametrically opposite projections 46 which when in operative position are arranged to respectively engage 70 the opposite ends of the arc flange 42 as shown in Figs. VII and VIII so that rotary movement of said clutch disk 45 effects corresponding rotary movement of said clutch ring 43. Said clutch disk 45 is operatively 75 connected with the exterior operating handle 47 by the shaft 48; the latter having flattened sides and fitting a similarly shaped opening in said disk 45 as indicated in Fig. IV. Said disk 45 is conveniently retained 80 on said shaft 48 by the screw 50 and washer 51, the latter bearing upon the washer 52 in contact with said disk as shown in Fig. VII.

Said coin inlet slot 38 is provided with the plane shutter 55, retained in reciprocatory relation with said plate 39 by the screws 56 and washers 57 shown in Figs. IV and V. As shown in Figs. V and VII said shutter 55 has the coin slot 59 arranged to register with the coin inlet slot 38 in the 90 box and the coin slot 41 in said clutch flange 42 as shown in Fig. VII to admit a coin to the carrier. Said shutter has the cam lug 60 which as shown in Fig. V is inclined with respect to the axis of rotation of the handle 47 and clutch disk 45 and projects within the recess 61 of the latter so as to be encountered by one or the other of the opposite inclined shoulders 62 and 63 of said clutch disk 45, whenever said handle 47 is turned 100 in either direction. Therefore, said shutter is shifted inwardly until its slot 59 is out of registry with said slots 38 and 41 and thus closes said inlet 38, upon rotation of the exterior handle 47 in the direction indicated by the arrows in Figs. I and IV to open the valve 12, and, said shutter is shifted outwardly to the position shown to reopen said inlet when said handle is returned in the opposite direction. It is to be understood that 110 when a coin 36 is dropped through said aligned slots 38, 59 and 41 into the position shown in Fig. III it operatively connects the clutch flange 42 with the carrier 28 so that when the handle 47 is turned in the direction of the arrows in Figs. I, III and IV, said coin slot 38 is first closed by the shutter 55 as above described, and said carrier is then turned with the gear 25 shown in Fig. VII engaging the gear 22, thus turning the nut gear 20 and raising the screw shaft 18 therethrough so as to uplift the yoke 17, rock the shaft 15 and open the valve 12 from the position shown in full lines in Fig. III to the position shown in dotted lines in Fig. II. Each rotary movement of said carrier 28 is limited to approximately one-half revolution by the abutment 44 which is then encountered by the end of the clutch flange 42 shown at the left hand side of Fig. III, and, 120 130

the connecting coin 36 cannot escape until such movement is completed, being guarded by the stationary flange 65 which is rigidly secured on the housing plate 30, conveniently by one of the screws 66 which rigidly secure said plate 30 on the housing 19, by engagement in the holes 67. Reverse rotation of the exterior handle 47 and said clutch flange 42 releases and dislodges the coin 36 from the carrier; the latter remaining stationary during such reverse rotation. Said guard flange 65 prevents the coin 36 from being carried back by the clutch, and it falls through the slot 68 into the coin chamber 10 where it is received in the till 70 which is conveniently constructed so as to be readily removed from the box as hereinafter described. Other coins 36 may be successively inserted in the inlet 38, and the operation 20 of said exterior handle 47 repeated as above described until the shaft 18 has been raised to the limit of its movement, sliding past said yoke 17.

I find it convenient to provide said shaft 18 with an index finger 71 which as shown in Figs. I and IX extends through the notch 72 in the edge of the cover plate 39; being visible exterior to the box 2 in conjunction with suitable graduations upon the adjacent wall 73 of the box 2, to indicate the quantity of gas for which prepayment is made. As shown in Fig. VIII said index 71 is swiveled in the head 74 which is rigidly connected with the screw shaft 18 which is free to rotate with respect to said index, the latter being confined by said plate 39.

Said valve 12 being manually opened by the operation of the prepayment mechanism as above described is automatically closed, after delivery of the quantity of gas predetermined by the number of coins inserted, by the meter mechanism within the casing 1; including the gear wheel 75 on the meter shaft 76. It is to be understood that 45 said shaft which is shown broken in Fig. VII may be of any desired length to carry the gear 75 within the meter casing 1, in operative relation with the meter mechanism. Said shaft 76 extends from said casing 1, through the gas tight stuffing box bearing 77 into the gear chamber 9 of said box 2 and has the worm 78 engaging the gear 79 on the vertical shaft 80 which is mounted to rotate in the bearing standard 81 on the top wall 82 of the housing 19. Said shaft is provided beneath said wall 82 with the price change gear 83, which as shown in Fig. XI, is rigidly but detachably connected therewith by the screw 84 and washer 85, the end of said shaft being squared as indicated in Fig. X. Said change gear 83 engages the idle gear 86 which is mounted on the stud shaft 87 removably secured in said wall 82 by the nut 88 as shown in Figs. VII and X. Said

gear 86 engages the gear 89 having the key 90 fitted in the keyway 91 of said screw shaft 18; said gear 89 being upheld by the sleeve 92 as best shown in Fig. VIII. It is to be understood that when said meter gear 75 is rotated in the direction of the arrow marked thereon in Fig. VIII said keyed gear 89 is turned in the direction indicated by the arrow in Fig. X and turns the screw shaft 18 so that the latter is lowered through 75 the nut gear 20 and consequently lowers the yoke 17 and permits the valve to close the port 6 when the full quantity of gas for which prepayment has been made has been delivered through the meter. Said housing 80 wall 82 is provided with several sockets 93 in which the stud shaft 87 may be selectively fitted, so that said idle gear 86 may be placed in different positions to engage price change gears 83 of different sizes, determined by the prices of the gas which is to be dispensed. That is to say, the gear 83 shown in Fig. X being for gas of the minimum price, if gas more expensive is to be dispensed a larger change gear 83 would be 90 substituted so as to turn the screw shaft 18 more rapidly and effect the closure of the valve 12 by the passage of less gas than would occasion the closure of said valve with the price change gear 83 of the size 95 shown in Fig. X. In this connection it may be observed that the lower wall 21 of the housing 24 has the opening 95 through which a screw driver may be inserted to remove the screw 84, release the gear 83 100 and permit the changes above contemplated, without removing the housing 24 from the box 2.

Said till 70 is rigidly engaged in removable relation with the box 2, conveniently 105 as follows:—As indicated in dotted lines in Fig. III, and elsewhere in full lines the stationary stud 96 which projects inwardly from the right hand wall of the box 2 fits the socket 97 in the till 70, and the latter is 110 provided with the lock 98 having the spring pressed bolt 99 which when in the locked position as shown in Fig. I engages the ledge 100 in said box 2. It is to be understood that said lock bolt 99 may be withdrawn by a key inserted in the lock nose 101 and that thereupon said till may be removed by swinging its left hand end downward and thus disengaging the right hand end from said stud 96. The construction above described is such that said till 70 is not only wholly concealed, in the normal position of the gasometer, but prevents access to the mechanism in the box. However, removal of said till affords access to the interior of the box and the prepayment mechanism therein, by way of the coin chamber 10, as follows: The cover 39 of the gear chamber 9 is normally rigidly secured 115 in said box 2 at its upper end by the sta 120

tionary stud 103 which projects inwardly from the upper wall of said box and fits the socket 104 in said cover; and, the lower end of said cover is rigidly connected with said box 2, by the screws 105, indicated in Fig. VII, which engage in the holes 106 in said cover indicated in Fig. IV and are accessible for removal with a screw driver inserted in said coin chamber 10 when said till 70 is removed from the box. Moreover, it may be observed that all of the gearing of the prepayment mechanism may be readily removed from the box 2 with the housing 19; the latter being normally rigidly secured in said box by the screws 107 shown in Figs. III and VIII, which extend through the holes 108 shown in Fig. XI and engage in holes in the box.

I do not desire to limit myself to the precise details of construction and arrangement herein set forth as it is obvious that various modifications may be made therein without departing from the essential features of my invention as defined in the appended claims.

25 I claim:—

1. A prepayment mechanism box inclosing a valve chamber, a gear chamber and a coin chamber; a stud in said gear chamber; a stud in said coin chamber; a removable cover for said gear chamber having a socket fitted to said stud therein; a screw engaging said cover within said coin chamber; a removable till in said coin chamber having a socket fitted to said stud therein, and a lock 35 engaging said box.

2. A prepayment mechanism box inclosing a gear chamber and a coin chamber; a stud in said gear chamber; a stud in said coin chamber; a removable cover for said gear chamber having a socket fitted to said stud therein; a screw engaging said cover within said coin chamber; and, a removable till in said coin chamber.

3. In prepayment mechanism, the combination with a box having a coin inlet slot; of a rotary coin carrier in said box; an exterior operating handle on said box, having means within said box arranged to engage a coin in said carrier to operate the latter; a reciprocating plane shutter arranged to control said inlet; and means positively operatively connecting said shutter with said exterior handle, including a rotary clutch element having its axis extending in the direction of movement of said shutter; whereby said inlet is closed when said handle is turned in one direction and opened when said handle is turned in the opposite direction.

60 4. In prepayment mechanism, the combination with a box having a coin inlet slot; of an exterior operating handle on said box; a reciprocating plane shutter arranged to control said inlet; and means positively operatively connecting said shutter with said

exterior handle for movement in two opposite directions; whereby said inlet is closed when said handle is turned in one direction and opened when said handle is turned in the opposite direction.

5. In prepayment mechanism, the combination with a box having a coin inlet slot; of an exterior operating handle on said box; a reciprocating plane shutter arranged to control said inlet, having a cam lug inclined with respect to the axis of rotation of said handle; and, a clutch disk connected to said handle, having a recess in registry with said cam lug and opposite inclined shoulders, whereby said inlet is closed when said handle is turned in one direction and opened when said handle is turned in the opposite direction.

6. In prepayment mechanism, the combination with a box having a coin inlet slot; of an exterior operating handle on said box; a reciprocating plane shutter arranged to control said inlet, having a cam lug inclined with respect to the axis of rotation of said handle; and, a clutch disk connected to said handle and to said shutter; whereby said inlet is closed when said handle is turned in one direction and opened when said handle is turned in the opposite direction.

7. In prepayment mechanism, the combination with a box having a coin inlet slot; of an exterior operating handle on said box; a plane shutter arranged to reciprocate axially with respect to said handle to control said inlet; and, a clutch disk connected to said handle and to said shutter; whereby said inlet is closed when said handle is turned in one direction and opened when said handle is turned in the opposite direction.

8. In prepayment mechanism, the combination with a box; of a rotary coin carrier in said box; an exterior operating handle on said box connected with means within said box arranged to engage a coin in said carrier to operate the latter, including a clutch disk having diametrically opposite projections, and, a clutch ring rotatable with respect to said carrier, having an arc flange with a coin slot; the opposite ends of said flange being respectively engaged by the projections on said disk.

9. In prepayment mechanism, the combination with a box having a removable cover; of a rotary coin carrier in said box; an exterior operating handle on said box carried by said cover and connected with means within said box arranged to engage a coin in said carrier to operate the latter, including a clutch disk carried by said cover and having diametrically opposite projections, and, a clutch ring rotatable with respect to said carrier, engaged by the projections on said disk; and means in said box retaining

said ring independently of said cover; whereby said cover may be removed with said disk without displacing said ring.

10. In prepayment mechanism, the combination with a box having a removable cover; of a rotary coin carrier in said box; an exterior operating handle on said box connected with means within said box arranged to engage a coin in said carrier to operate the latter, including a clutch disk, carried by and removable with said cover, engaging a clutch ring rotatable with respect to said carrier; and means retaining said ring in said box, independently of said cover.

15. 11. In prepayment mechanism, the combination with a rotary coin carrier having diametrically opposite projections with recesses to receive a coin extending transversely with respect to the axis of the carrier; of a clutch ring rotatable with respect to said carrier, having an arc flange with a coin slot adapted to register with the recesses in said projections; an operating handle; and a clutch element rigidly connected with said handle, arranged for adjustable connection with said clutch ring, independently of said carrier; whereby said clutch ring and carrier may be operatively connected by a coin engaged at its periphery in said recesses, projecting in the slot in said flange and engaged at its periphery in the latter.

12. In prepayment mechanism, the combination with a rotary coin carrier having relatively stationary projections with recesses to receive a coin extending from one projection to the other transversely with respect to the axis of the carrier; of a clutch ring rotatable with respect to said carrier, having an arc flange with a coin slot adapted to register with the recesses in said projections; whereby said clutch ring and carrier may be operatively connected by a coin engaged at its periphery in said recesses, projecting in the slot in said flange and engaged at its periphery in the latter.

13. In prepayment mechanism, the combination with a rotary coin carrier having a shaft, and diametrically opposite projections with recesses to hold a coin extending in a plane transversely with respect to the axis of said shaft; of a clutch ring rotatable with respect to said carrier and having an arc flanged with a slot adapted to register with said recesses; and, a clutch disk having projections arranged to respectively encounter the opposite ends of said arc flange; whereby said disk and ring are continuously engaged for rotary movement independently of said carrier, and said carrier may be rotatably connected therewith by the peripheral engagement of a coin in said slot and recesses.

14. In prepayment mechanism, the combination with a rotary coin carrier having a shaft, and recesses to hold a coin extending

in a plane transversely with respect to the axis of said shaft; of a clutch ring rotatable with respect to said carrier and having an arc flange with a slot adapted to register with said recesses; and, a clutch disk having projections arranged to respectively encounter the opposite ends of said arc flange; whereby said disk and ring are continuously engaged for rotary movement independently of said carrier and said carrier may be rotatably connected therewith by the peripheral engagement of a coin in said slot and recesses.

15. In prepayment mechanism, the combination with a rotary coin carrier having a shaft, and recesses to hold a coin extending in a plane transversely with respect to the axis of said shaft; of a clutch ring rotatable with respect to said carrier and having an arc flange with a slot adapted to register with said recesses; and, a clutch disk engaging said ring; whereby said disk and ring are continuously engaged for rotary movement independently of said carrier, and said carrier may be rotatably connected therewith by the peripheral engagement of a coin in said slot and recesses.

16. In prepayment mechanism, the combination with a box having a coin inlet slot; of an exterior operating handle on said box; a clutch disk in said box rotatably engaged by said handle and having diametrically opposite projections; a clutch ring mounted to turn upon the axis of said handle, having an arc flange with a slot adapted to register with the slot in said box, and having its opposite ends engaged by said projections on said disk.

17. In prepayment mechanism, the combination with a box having a coin inlet slot; of a clutch ring having an arc flange with a slot adapted to register with the slot in said box; a clutch disk having projections respectively arranged to engage the opposite ends of said arc flange; and, a handle exterior to said box operatively connected with said clutch ring.

18. In prepayment mechanism, the combination with a box having a removable cover including a coin inlet slot; of a rotary coin carrier in said box having its axis of rotation at right angles to the length of said slot; an exterior operating handle on said box carried by said cover and detachably connected with means within said box arranged to engage a coin in said carrier extending in a plane at right angles to the axis of said carrier to operate the latter, whereby said cover may be removed with said handle, independently of said carrier.

19. In prepayment mechanism, the combination with a box having a coin inlet slot; of an exterior operating handle on said box; a plane shutter arranged to reciprocate in a plane in contact with said box and axially

6
with respect to said handle to open and close said slot; and, means operatively connecting said shutter with said exterior handle; whereby said slot is closed when said handle is turned in one direction and opened when said handle is turned in the opposite direction.

20. A prepayment mechanism box inclosing a gear chamber; a stud in said gear chamber; a removable cover for said gear chamber having a socket fitted to said stud therein; and, a screw engaging said cover within said box.

21. In prepayment mechanism, the combination with a box having a cover; of a rotary coin carrier having a shaft mounted for rotation in said box, and recesses to hold a coin extending in a plane transversely with

respect to the axis of said shaft; a clutch ring rotatable with respect to said carrier 20 and having an arc flange with a slot adapted to register with said recesses; a clutch disk, carried by said cover, engaging said ring; and, means preventing relative movement of said clutch disk and ring; whereby said disk 25 and ring are continuously engaged for rotary movement together, when assembled, but may be axially separated, only when said cover is removed.

In testimony whereof, I have hereunto 30 signed my name at Philadelphia, Pennsylvania, this 18th day of June, 1910.

JAMES BARTON KAIGHN.
